PICNIC JUG OR SIMILAR ARTICLE

Nathan W. Roop, Columbus, Ohio, assignor to Columbus
Plastic Products, Inc., Columbus, Ohio, a corporation of Ohio

Filed Feb. 20, 1961, Ser. No. 63,987

Term of patent 14 years

(Cl. D58—17)

191,723

FIG. 1 is an exploded perspective view of a picnic jug or similar article showing my new design, and showing the outer closure member removed from the body of the jug;

FIG. 2 is a side elevational view of the picnic jug or similar article, showing the outer closure in position upon the body of the jug; and

FIG. 3 is a top plan view thereof.

I claim:

The ornamental design for a picnic jug or similar article, substantially as shown.
